UNITED STATES PATENT OFFICE.

HENRY C. BUDDENBERG, OF CINCINNATI, OHIO.

DEVICE FOR PREVENTING THE ESCAPE OF EFFLUVIA FROM PRIVY-VAULTS AND DRAINS.

SPECIFICATION forming part of Letters Patent No. 282,437, dated July 31, 1883.

Application filed October 2, 1882. (No model.)

To all whom it may concern:

Be it known that I, HENRY C. BUDDENBERG, of Cincinnati, Hamilton county, Ohio, have invented a new and useful Device for Preventing the Escape of Effluvia from Privy-Vaults and Drains into Dwellings, of which the following is a specification.

This device consists of a flap or valve which at all times, except during use of the privy or urinal, closes the passage between the vault or drain and the dwelling, and which, by the simple act of occupancy of the privy or urinal, automatically throws open, for the time being, the said flap or valve, which latter again automatically closes the instant of the disuse of the privy or urinal.

In the accompanying drawings, Figure 1 is a vertical section of a privy provided with my invention, the same being shown in its normal condition—that is to say, with the flap or valve closed. Figs. 2 and 3 represent the seat with valve open by sections, respectively, at right angles and parallel to the seat-front. Fig. 4 is a vertical section, which shows, in the closed condition, a water-closet provided with my improvement. Fig. 5 is a section at right angles to the section Fig. 4 of such a water-closet in the open condition. Fig. 6 is a top view of the casting which constitutes my valve-seat. Fig. 7 shows, by vertical section, an application of the same principle to a urinal.

A may represent a vault or cesspool; B, privy-floor; C, trunk or riser, to which is secured by hinge D the privy-seat E.

F represents one of two springs that operate to uphold the front edge of the seat, as shown in Fig. 1. Said seat, when unoccupied, (acting through rods G, whose racks H mesh in pinions I upon shaft J of flap or valve K,) operates to hold said flap to the closed position shown in Fig. 1. The same seat, when pressed down by an occupant, operates through the same members to open the flap, and during such occupancy to hold the flap open, as seen in Figs. 2 and 3.

In Figs. 4 and 5 the same principle is shown applied to a water-closet. In this form the flap and its pinion are so related to the operating-rack as to act as a lever of the first class, the flap being opened by an ascending instead of a descending movement of the rack H, which in this modification is connected with rod G through the medium of a short lever, L. In Fig. 4 the bowl M of the water-closet is of stoneware, and occupies an iron trunk, which constitutes the flap-seat. In Fig. 5 the bowl and trunk constitute a single casting.

In the form shown in Figs. 1, 2, and 3 journal-bearings N of shaft J are fastened to the under side of the floor B. In the form shown in Figs. 4, 5, and 6 the shaft J is journaled in sockets that constitute cast projections p from the walls of a cast chamber, P.

Q shows a hydrant service-pipe communicating with a valve or cock, R, whose stem S, being depressed by descent of the privy-seat, permits water to discharge under deflector T and flush the bowl during the occupancy of the privy-seat.

I claim as new and of my invention—

1. The combination, with the hopper or soil-pipe of a water-closet, privy, or urinal, of a flap or valve, K, adapted to be operated automatically by the weight of an occupant through the medium of pinion I, rack H, and suitably interposed levers, substantially as and for the purpose set forth.

2. The combination of spring-seat E D, rods G S, rack H, pinion I, flap K, lever L, bowl M, and flush-cock R, substantially as and for the purpose set forth.

In testimony of which invention I hereunto set my hand.

HENRY C. BUDDENBERG.
